LAMP MOUNTING

Filed Aug. 31, 1929

UNITED STATES PATENT OFFICE

CARL H. LARSON, OF ELKHART, INDIANA, ASSIGNOR TO THE ADLAKE COMPANY, A CORPORATION OF ILLINOIS

LAMP MOUNTING

Application filed August 31, 1929. Serial No. 389,847.

This invention relates to lamp mountings such as may advantageously be employed in railway signals, such as switch and semaphore lamps.

5 The principal objects of this invention are to provide improved means for focusing a lamp with respect to the lens or reflector with which it is associated and to protect the lamp from injury due to excessive vibration and 10 jarring.

Other and further objects and advantages will become apparent as the disclosure proceeds and the description is read in conjunction with the accompanying drawings, in 15 which:

Fig. 1 is a plan view of the improved lamp mounting; and

Figs. 2 and 3 are side elevations of the same.

In the preferred embodiment of this invention, the base 10, which may be of any suitable shape, is provided with upstanding studs or posts 11, 12 and 13 which carry an annular plate 14 of insulating material, such as bakelite, held in proper spaced relationship from 25 the base 10 by suitable nuts 15. The lower ends of the posts 11, 12 and 13 which extend through the base 10 are rounded, as at 16, forming a seat for the lamp mounting. A connecting bolt 17 secures and firmly seats the 30 improved lamp mounting to the outer shell or casing 18 (only partly shown) of the signal lamp.

A transformer 19 of conventional form is suspended from the annular plate 14 by suspension bolts 20 and 21 which are provided with spacer sleeves 22 and 23 respectively for rigidly holding the transformer in place. The transformer 19, however, is not essential in this construction it being used only in case 40 it is necessary to adapt the available current to the requirements of the bulb.

The upper portions of the posts 11, 12 and 45 13 extend above the upper face of the annular plate 14 and are threaded to receive thumb nuts 24, 25 and 26. These nuts are provided with a grooved neck portion 30, preferably V-shaped in cross section, to receive the outer curved extremity of coiled springs 27, 28 and 29 respectively, the inner ends of which support a lamp socket 31. These springs are

under sufficient tension so as to support the lamp socket in substantially the same plane as the coil springs.

Suitable binding posts 32 and 32^a are provided on the annular plate 14 for securing the lead-in wires and the wires connecting with the transformer and the lamp socket. The wiring need not further be described since it is as is usual in such constructions.

It is essential in railway signal lamps that the filament of the lamp be accurately positioned at the focal point of the associated lens. In the present case this is accomplished by adjustment of the thumb nuts 24, 25 and 26 from which the lamp socket 31 is suspended by the springs 27, 28 and 29, the adjustment being continued until the filament 33 of the lamp 33^a coincides with the focal point of the lens. A vertical adjustment is obtained by simultaneously screwing the thumb nuts 24, 25 and 26 an equal distance up or down the posts while a lateral adjustment is obtained by screwing one of the thumb nuts at a time. This adjustment is of the familiar universal type 75 which permits of adjustment of the lamp filament to any given point within a limited range. In this way the lamp filament 32 may be accurately positioned at the focal point of the lens.

The adjustment is reliably maintained by the friction between the encircling wire loop of the spring and the nut, increased by the spring tension and the binding of the wire within the V-shaped groove in the nut. The 85 use of lock nuts is avoided, a consideration of importance especially in signal lamps in which access to the adjusting mechanism is obtained only through restricted openings in the casing, rendering the use of tools almost impossible without drawing the support from the casing.

Inasmuch as the lamp is suspended freely by the springs which are under tension there is little or no danger of the filament 33 being 85 injured or broken by excessive vibration of the lamp mounting.

Furthermore the construction is such that the resilient mounting of the lamp socket does not interfere with or affect the focusing 100

of the lamp with respect to its associated lens and the displacement of the lamp due to vibration is but momentary the lamp filament returning to its initial position at the focal point of the lens almost immediately.

The improved lamp mounting has been described as employed in a railway signal lamp but it is obvious that it may advantageously be used in various other lamp structures wherein the universal adjustment of the lamp and the resilient mounting thereof are desirable features.

It is, of course, apparent that various changes and modifications may be made in the detail of the lamp mounting illustrated without departing from the spirit of this invention as expressed in the appended claims forming a part hereof.

I claim as my invention:

20 1. A lamp mounting comprising in combination a base, a plurality of posts rising from said base, and threaded at their upper ends, a lamp socket positioned between said posts, springs extending between said posts and said socket for supporting the latter, thumb nuts for said posts, said nuts being adapted to carry the outer extremities of said springs for permitting a universal adjustment of the lamp socket.

25 30 2. A lamp support comprising in combination, a plurality of upstanding posts threaded at their upper ends, thumb nuts for said posts, a lamp socket positioned centrally of said posts, and resilient elements 35 extending between said thumb nuts and said lamp socket for supporting the latter substantially in a plane with said resilient elements.

35 40 45 50 3. A lamp support comprising in combination, a plurality of upstanding posts threaded at their upper ends, grooved thumb nuts cooperating with said threaded portion of said posts, and a lamp socket positioned centrally of said posts and springs extending between said lamp socket and said nuts for supporting the socket, the outer curved extremities of the springs encircling said grooved portion of the nuts and furnishing a frictional locking of the nuts in adjustment.

55 60 5. A lamp support comprising in combination, a plurality of upstanding posts threaded at their upper ends, thumb nuts cooperating with said threaded portion of said posts, a lamp socket positioned centrally of said posts and springs extending between said lamp socket and said nuts for supporting the socket, said thumb nuts being provided with an annular V-shaped groove for receiving the outer curved extremities of the springs for furnishing a frictional locking of the nuts in adjustment.

65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

combination of a base, a plurality of posts projecting from the base, a lamp socket between the posts, radial elastic members secured to the socket, and means carried by the posts supporting the outer extremities of the elastic members and capable of independent graduated movement along the posts for effecting a universal adjustment of the lamp.

In testimony whereof, I affix my signature.

CARL H. LARSON.
